CLAIM

The ornamental design for a bag, as shown and described herein.

DESCRIPTION

FIG. 1 is a front, left side, top perspective view according to my design for a bag.

FIG. 2 is a front view of the bag shown in FIG. 1.

FIG. 3 is a rear view of the bag shown in FIG. 1.

FIG. 4 is a right side view of the bag shown in FIG. 1.

FIG. 5 is a left side view of the bag shown in FIG. 1.

FIG. 6 is a top view of the bag shown in FIG. 1; and,

FIG. 7 is a bottom view of the bag shown in FIG. 1.

The broken lines of the drawings represent stitching that does not form part of the claimed design.

1 Claim, 7 Drawing Sheets(56)
